(57) CLAIM

The ornamental design for a dual washbasins and furniture stand, as shown and described.

DESCRIPTION

FIG. 1 is a top, front, left side perspective view of a dual washbasins and furniture stand showing my new design with one of the two front rungs shown in cross-section in order to typically show the profile thereof;

FIG. 2 is a front elevational view thereof (the rearview being a mirror image); and,

FIG. 3 is a left end elevational view thereof (the right side being a mirror image).

1 Claim, 2 Drawing Sheets

FIG. 1

FIG. 3
